UNITED STATES PATENT OFFICE

141,127

DESIGN FOR A WALL CABINET

Jacques Stanitz, Warren, Ohio, assignor to Mullins Manufacturing Corporation, Salem, Ohio, a corporation of New York

Application March 2, 1945, Serial No. 118,222

Term of patent 7 years

(CL D33—19)

To all whom it may concern:

Be it known that I, Jacques Stanitz, a citizen of the United States, residing at Warren, in the county of Trumbull and State of Ohio, have invented a new, original, and ornamental Design for Wall Cabinet, of which the following is a specification, reference being had to the accompanying drawing forming part thereof.

The single figure in the drawing is a perspective view of a wall cabinet showing my new design. The rear of the cabinet, not shown, is plain and the other side thereof is the same as illustrated. The characteristic features of my design are shown by means of full lines in the drawing.

I claim:

The ornamental design for a wall cabinet, substantially as shown and described.

JACQUES STANITZ.
